Primary Examiner — George D Kirschbaum

Assistant Examiner — Jennifer Watkins

(57) **CLAIM**

The ornamental design for hat, as shown and described.

DESCRIPTION

1.-3. Hats

Fig. 1.1 is a front view of a hat showing our new design. Fig. 1.2 is a side view thereof; and

Fig. 1.3 is a rear view thereof.

Fig. 2.1 is a front view showing a second embodiment of the hat of figure 1.1.

Fig. 2.2 is a side view thereof; and

Fig. 2.3 is a rear view thereof.

Fig. 3.1 is a front view of a third embodiment of the hat of figure 1.1.

Fig. 3.2 is a side view thereof; and

Fig. 3.3 is a rear view thereof.

The broken line showing of a hat is for the purpose of illustrating portions of the article and forms no part of the claim.

1 Claim, 9 Drawing Sheets
